UNITED STATES PATENT OFFICE.

ARTHUR L. STAPLES, OF NEW HAVEN, CONNECTICUT, ASSIGNOR TO WINCHESTER REPEATING ARMS COMPANY, OF NEW HAVEN, CONNECTICUT, A CORPORATION OF CONNECTICUT.

SPOTLIGHT.

Application filed December 19, 1921. Serial No. 523,256.

To all whom it may concern:

Be it known that I, ARTHUR L. STAPLES, a citizen of the United States, residing at New Haven, in the county of New Haven, 5 State of Connecticut, have invented certain new and useful Improvements in Spotlights; and I do hereby declare the following to be a full, clear, and exact description of the invention, such as will enable others skilled 10 in the art to which it appertains to make and use the same.

The present invention relates to battery hand lamps of the type disclosed and claimed in my co-pending application, Serial 15 Number 509,885, filed October 24th, 1921, wherein the character of the beam of light can be altered by varying the relative position of the lamp and reflector.

It is an object of the present invention 20 to provide a hand lamp in which the reflector has a substantially fixed position in the casing, and in which the desired change in the character of the beam of light delivered by the hand lamp is effected by shifting 25 the bulb with respect to the reflector.

In the preferred embodiment, the battery is permitted to shift axially with the lamp bulb.

It is a further object of the present invention 30 to compactly group the several elements, to provide for the use of a casing of minimum length, to provide for easy manufacture and assembly of the several parts, to provide for easy access to various 35 parts of the hand lamp mechanism, as for purposes of repair, to insure against short-circuiting of the battery and inadvertent lighting of the lamp, and to secure other objects and advantages as hereinafter pointed 40 ed out more at length.

In the accompanying drawings:

Fig. 1 is a sectional elevation of one embodiment of the invention.

Fig. 2 is a fragmentary section of the 45 same embodiment.

Fig. 3 is a section on the line 3—3 of Fig. 1.

Fig. 4 is a section on the line 4—4 of Fig. 1.

Fig. 5 is a perspective view of a modified form of lamp supporting bridge.

Fig. 6 is a sectional elevation of an adjusting collar suitable for use with the bridge of Fig. 5.

Fig. 7 is a perspective view of still an-

other modified form of lamp supporting bridge.

Fig. 8 is a section on the line 8—8 of Fig. 7.

In the embodiment illustrated, the hand 60 lamp comprises a casing 1 of insulating material, such as fiber, in which are a plurality of dry cells 2, placed end to end in a pasteboard carton in conformity with usual practice. 65

The naked bottom of the lowermost dry cell rests on and makes electrical connection with a coil spring 3, carried by a metal bottom cap 4, threaded to a collar 5 on casing 1. 70

A metal strip 6, connects collar 5 with the switch housing 7, in conformity with usual practice.

At the opposite, or front end, of casing 1, and forming a part thereof, is a flaring 75 metal head 8, fastened to the fiber tube by rivets 9 and having its front portion threaded to receive a lens supporting ring 10. A reflector 11, substantially parabolic in outline, has its outer flange gripped between collar 80 10 and the front edge of head 8, so that the reflector is clamped in fixed relation to the casing. The lens 12 may be plane, as shown, or it may be curved.

The incandescent lamp bulb 13 is threaded 85 into a lamp support comprising a cylindrical block 14, of insulating material. A metal rivet 15 passes through the bottom of the block and makes electrical connection between the inner lamp terminal and the upper 90 electrode 16 of the battery. Electrical connection to the threaded or outer terminal of the lamp is made through a yielding contact finger 17, bent up from a metal plate 18, which is permanently held against the 95 bottom of the lamp-supporting block 14 by the central rivet 15. An annular flange on the bottom of block 14 and an insulating washer 19 keep this metal plate out of electrical connection with rivet 15. This metal 100 plate 18 has a finger, or lug, 20, (Fig. 3) against which yieldingly bears the inwardly bent end of a stationary conductive strip 21. This strip is secured to the fiber tube by a rivet 22, and its rear end 23 is bent up 105 to pass out through a slit in the fiber tube so that it may serve as one of the contacts of a manually operative switch mechanism.

The switch mechanism comprises a thumb-actuated push button 24 at one end of a 110

yielding conductor fastened to and in electrical connection with housing 7 by a rivet 25. By inward pressure on the push button 24, electrical connection can be established between the bottom electrode of the battery and the outer terminal of the lamp. A sliding thumb piece 26 carries a finger 27 which, on inward pressure of the push button 24, will disengage from a slot in said yielding conductor and can be pushed forward to hold the switch in position for continually lighting the lamp.

The insulating block 14, into which the incandescent lamp is threaded, fits tightly within a bridge 28, whereby it can be moved axially of the hand lamp to adjust the position of the lamp bulb with respect to reflector 11. The inner edge of reflector 11 terminates in an extension 29, through which the lamp support 14 can freely slide.

In the embodiment illustrated in Figures 1 to 4, inclusive, the lamp supporting bridge is a sheet metal stamping, having three rigid arms 30, 31 and 32, each of which passes through a longitudinal slot in the fiber tube and is engaged by an adjustable sleeve comprising two elements, 33 and 34, flanged together as shown in Fig. 1, and having threaded engagement with the rear portion of the flaring metal head 8. It is of course obvious that the bridge 28 may be made of solid metal and having three rigid solid metal arms such as the integral arms of the embodiment shown in Figure 5. This bridge is electrically insulated from the metal plate 18 and its finger 20 by an annular flange 35 on block 14. The block fits so snugly within a central opening in the bridge that it is not likely to rotate therein during normal use of the hand lamp.

In the arrangement above described, the battery circuit is from battery terminal 16 through rivet 15 to the inner terminal of the lamp, then through the lamp to finger 17, plate 18, and lug 20, and then through conductor 21, push button 24, housing 7, conductor 6, collar 5, cap 4 and spring 3 to the other terminal of the battery.

The lamp can be flashed, as in signaling by the Morse code, or it can be burned continuously, by suitable manipulation of the elements 24 and 26. The character of the beam of light can be varied at will by rotating the adjusting sleeve and thereby causing the lamp supporting bridge to travel along the slots in the fiber casing, thus moving the lamp bulb with respect to the reflector and so changing the spread of the beam of light delivered by the reflector. The coil spring 3 at the bottom of the casing holds the battery always in contact with rivet 15, irrespective of the forward or backward movements of the lamp supporting bridge and the resultant axial movements of the lamp and battery.

In the embodiment illustrated in Figures 5 and 6, the lamp supporting bridge 36 is of solid metal, excepting that arm 37 is initially separate from the remainder of the bridge and is slipped into position and soldered fast, after the bridge has been installed in the adjusting sleeve 38. This permits the use of a one piece adjusting sleeve as shown in Fig. 6.

In the embodiment illustrated in Figures 7 and 8, the supporting bridge 39 is of relatively thin sheet metal and initially has its arms bent at 40 (Fig. 8) so that the arms can be introduced into the one piece adjusting sleeve of Fig. 6. When once in place, the bend at 40 is flattened out as indicated in dotted lines and the bridge then is permanently mounted in the adjusting sleeve and is ready for the introduction of the insulating lamp supporting block 14.

Other changes in details of construction and in mode of assembly can be made without departing from the spirit of the invention as defined by the appended claims.

In the embodiments shown in the drawings, the tube casing is of insulating material, but the present invention is applicable to a metal casing by merely insulating the conductor 21 from the casing, in known manner. The battery is well protected against short circuit, and inadvertent lighting of the lamp will not occur when the hand lamp is laid on a metal surface or placed among metal tools.

I claim:

1. In a hand lamp, the combination of a casing, a battery and a lamp therein arranged coaxially thereof, a reflector for said lamp, and screw threaded means surrounding said casing for positively moving said lamp with respect to said reflector to change the spread of the beam of light delivered by said lamp, said screw threaded means being adapted to move said lamp progressively as said means is turned.

2. In a hand lamp, the combination of a casing, a battery and a lamp therein, a reflector for said lamp, and means encircling and threaded to the front end of said casing for moving said lamp with respect to said reflector to change the spread of the beam of light delivered by said hand lamp.

3. In a hand lamp, the combination of a casing, a battery and a lamp therein, a reflector for said lamp, an adjustable sleeve encircling the front end of said casing, and means actuated by said sleeve for moving said lamp and battery with respect to said reflector to change the spread of the beam of light delivered by said hand lamp.

4. In a hand lamp, the combination of a casing having longitudinal slots, a battery and a lamp in said casing, a reflector for said lamp, means movable along said slots to move the lamp with respect to the focus

of said reflector to change the spread of the beam of light delivered by said hand lamp, and screw threaded means associated with said first named means for positively moving said first named means along said slots 5 as said screw threaded means is turned.

5. In a battery hand lamp, the combination of a casing having longitudinal slots, a battery and a lamp in said casing, a reflector for said lamp, a bridge in which said lamp is supported, and means encircling and threaded to said casing for moving said bridge and lamp with respect to said reflector to change the spread of the beam of 10 light delivered by said hand lamp.

6. In a hand lamp, the combination of a casing, a battery and a lamp therein, a reflector for said lamp, an adjusting sleeve encircling the front end of said casing, and 15 a bridge by which said lamp is supported, said bridge being in engagement with said adjusting sleeve to move said lamp with respect to said reflector when the character of the beam of light delivered by said hand 20 lamp is to be altered.

7. In a hand lamp the combination of a casing, a battery and a lamp therein arranged coaxially thereof, a reflector for said lamp having a cylindrical extension, an insulating lamp support mounted to slide in 30 said extension, an adjustable sleeve encircling and threaded to the front end of said casing, and means actuated by said sleeve for moving said lamp support along the axis of 35 said reflector to change the spread of the beam of light delivered by said hand lamp.

8. In a hand lamp the combination of a casing, a battery and a reflector arranged coaxially within said casing, a cylindrical 40 lamp support of insulating material mounted to move along the axis of said reflector, a lamp in said support, an adjusting sleeve threaded to the end of said casing, a bridge actuated by said adjusting sleeve and oper- 45 atively connected to move said insulating lamp support and thereby change the character of the beam of light delivered by said hand lamp, a closure for the rear end of said casing, and a coiled spring carried by said 50 closure and urging said battery toward said lamp to maintain electrical connection with the inner terminal of the lamp regardless of its axial movements.

9. In a battery hand lamp the combination of a casing having longitudinal slots, a reflector in said casing having a tubular extension, an insulating lamp support positioned to slide along said extension, a lamp threaded therein and a bridge carrying said 55 lamp support and having arms extending through and movable along said longitudinal slots; substantially as described.

10. In a hand lamp the combination of a casing having longitudinal slots, a metal 60 bridge having rigid arms passed through

and movable along said slots, an insulating support snugly fitted in an opening in said bridge, a lamp in said support, a reflector for said lamp, and means acting on the arms of said bridge to shift said lamp along the 70 axis of said reflector to change the character of the beam of light delivered by the hand lamp.

11. In a battery hand lamp the combination of a casing, a battery and a lamp arranged coaxially within said casing, a reflector for said lamp, a sleeve encircling the front end of said casing, means actuated by said sleeve for moving said lamp with respect to said reflector to change the spread 75 of the beam of light delivered by said hand lamp, and a coiled spring at the rear end of said casing urging said battery toward said lamp to maintain electrical connection therewith irrespective of axial movement of said 80 lamp.

12. In a hand lamp the combination of a casing, a battery therein, a flaring metal head rigidly attached to the front end of said casing, a lens holder threaded to said 90 head, a reflector clamped between said holder and the end of said head, a lamp support mounted to slide in and out of said reflector, a lamp coaxially with said casing and carried by said support, an adjusting sleeve 95 threaded to said flaring metal head, a bridge actuated by said adjusting sleeve and adapted to shift said lamp support along the axis of said casing and thereby change the character of the beam of light delivered 100 by said hand lamp, a closure for the rear end of said casing, and a spring carried by said closure and urging said battery toward said lamp to maintain electrical connection with the inner terminal of the lamp 105 regardless of its axial adjusting movements.

13. In a hand lamp the combination of a casing, a battery therein, a flaring metal head rigidly attached to the front end of said casing, a lens holder threaded to said head, 110 a reflector clamped between said holder and the end of said head, said reflector having a cylindrical extension, a cylindrical lamp support of insulating material mounted to slide in the extension of said reflector, a lamp coaxial with said casing and threaded into said support, an adjusting sleeve threaded to said flaring metal head, a metal bridge actuated by said adjusting sleeve and having an opening in which the insulating 115 lamp support fits tightly so that said support will move with said bridge axially of said hand lamp and thereby changing the character of the beam of light delivered by said hand lamp, a closure for the rear end of said casing, and a coiled spring carried by said closure and urging said battery toward said lamp to maintain electrical connection with the inner terminal of the lamp regardless of its axial adjusting movements. 120

125 130

14. In a hand lamp the combination of a casing, a battery therein, a flaring metal head rigidly attached to the front end of said casing, a lens holder threaded to said head, a reflector clamped between said holder and the end of said head, said reflector having a cylindrical extension, a cylindrical lamp support of insulating material mounted to slide in the extension of said reflector, a lamp coaxial with said casing and threaded into said support, a plate carried by said support and having a yielding finger in contact with the outer lamp terminal, a lug on said metal plate, a conductor yieldingly bearing against said lug, an adjusting sleeve threaded to said flaring metal head, a metal bridge actuated by said adjusting sleeve and having an opening in which the insulating lamp support fits tightly so that said support will move with said bridge axially of said hand lamp and thereby change the character of the beam of light delivered by said hand lamp, a closure for the rear end of said casing, a coiled spring carried by said closure and urging said battery toward said lamp to maintain electrical connection with the inner terminal of the lamp regardless of its axial movement, and switch

mechanism between said coiled spring and said yielding conductors.

30

15. In a hand lamp, the combination of a casing a battery and a lamp arranged co-axially within said casing, a reflector for said lamp, a sleeve encircling the front end of said casing, and means actuated by said sleeve for moving said lamp with respect to said reflector to change the spread of the beam of light delivered by said hand lamp.

35

16. In a hand lamp, the combination of a casing, a battery and a lamp therein, a reflector for said lamp, and a sleeve encircling the front end of said casing and threaded thereto, said sleeve being operatively connected for moving said lamp with respect to said reflector to change the spread of the beam of light delivered by said hand lamp.

40

17. In a hand lamp, the combination of a casing, a battery and a lamp therein, a reflector for said lamp, an adjustable sleeve encircling the front end of said casing, and means actuated by said sleeve for moving said lamp with respect to said reflector to change the spread of the beam of light delivered by said hand lamp.

45

18. In testimony whereof I affix my signature. 50
ARTHUR L. STAPLES.
